US00D683397S

(12) **United States Design Patent**
Bratter et al.

(10) **Patent No.:** **US D683,397 S**
(45) **Date of Patent:** **** May 28, 2013**

(54) **PAD OF LABELS**

(75) Inventors: **Adam Bratter**, Newport Coast, CA (US); **Douglas Wilson**, San Dimas, CA (US); **Debbie Caton**, Redondo Beach, CA (US); **Tracey Glenn**, Altadena, CA (US); **Peggy Diaz**, Ontario, CA (US)

(73) Assignee: **Avery Dennison Corporation**, Pasadena, CA (US)

(**) Term: **14 Years**

(21) Appl. No.: **29/360,189**

(22) Filed: **Apr. 21, 2010**

(51) LOC (9) Cl. **19-01**

(52) U.S. Cl.

USPC **D19/1**

(58) **Field of Classification Search**

USPC D20/10, 11, 19, 22–28, 40, 99; 283/51, 283/56, 61, 62, 71, 81, 103, 106, 115; D19/1, D19/2, 26, 86, 9, 10; D28/4; 2/181; 40/124.01–124.09, 124.11–124.19, 124.191, 40/299.01, 300, 303, 305, 306, 309, 310, 40/312, 359, 360, 625, 363, 638, 661; 156/6; 206/447; 428/40.1, 42.1–42.3, 914, 43, 195.1; 116/234; 281/38, 41, 42, 44; 462/63, 900; 221/45; D9/772

(57) **CLAIM**

We claim the ornamental designs for pad of labels, as shown and described.

DESCRIPTION

FIG. 1 is a top perspective view of two pads of labels and a shared bottom backing card embodying our new design.

FIG. 2 is a top plan view of the two pads of labels of FIG. 1.

FIG. 3 is a bottom plan view of the two pads of labels of FIG.

1.

FIG. 4 is a front-edge elevational view of the two pads of labels of FIG. 1.

FIG. 5 is a back-edge elevational view of the two pads of labels of FIG. 1.

FIG. 6 is a left-side elevational view of the two pads of labels of FIG. 1.

FIG. 7 is a right-side elevational view of the two pads of labels of FIG. 1.

FIG. 8 is a top perspective view of three pads of labels and a shared bottom backing card embodying our new design.

FIG. 9 is a top plan view of the three pads of labels of FIG. 8.

FIG. 10 is a bottom plan view of the three pads of labels of FIG. 8.

FIG. 11 is a front-edge elevational view of the three pads of labels of FIG. 8.

FIG. 12 is a back-edge elevational view of the three pads of labels of FIG. 8.

FIG. 13 is a left-side elevational view of the three pads of labels of FIG. 8.

FIG. 14 is a right-side elevational view of the three pads of labels of FIG. 8.

FIG. 15 is a top perspective view of another two pads of labels and a shared bottom backing card embodying our new design.

FIG. 16 is a top plan view of the two pads of labels of FIG. 15.

FIG. 17 is a bottom plan view of the two pads of labels of FIG. 15.

FIG. 18 is a front-edge elevational view of the two pads of labels of FIG. 15.

FIG. 19 is a back-edge elevational view of the two pads of labels of FIG. 15.

FIG. 20 is a left-side elevational view of the two pads of labels of FIG. 15.

FIG. 21 is a right-side elevational view of the two pads of labels of FIG. 15.

FIG. 22 is a top perspective view of another two pads of labels and a shared bottom backing card embodying our new design.

FIG. 23 is a top plan view of the two pads of labels of FIG. 22.

FIG. 24 is a bottom plan view of the two pads of labels of FIG. 22.

FIG. 25 is a front-edge elevational view of the two pads of labels of FIG. 22.

FIG. 26 is a back-edge elevational view of the two pads of labels of FIG. 22.

FIG. 27 is a left-side elevational view of the two pads of labels of FIG. 22; and,

FIG. 28 is a right-side elevational view of the two pads of labels of FIG. 22.

In the drawings, the broken lines represent perforations.
